UNITED STATES PATENT OFFICE.

ALONZO HICKS, OF NEW YORK, N. Y., ASSIGNOR TO HIMSELF AND
BENJAMIN F. CONWAY, OF SAME PLACE.

ACETYLENE-GAS GENERATOR.

SPECIFICATION forming part of Letters Patent No. 650,681, dated May 29, 1900.

Application filed April 28, 1899. Serial No. 714,784. (No model.)

To all whom it may concern:

Be it known that I, ALONZO HICKS, a citizen of the United States, residing in the city, county, and State of New York, have invented an Improvement in Acetylene-Gas Generators, of which the following is a specification.

The object of the present invention is to supply the calcium carbid gradually into the generator and to stop the supply whenever the gas-holder is sufficiently full, and in addition to this the discharge-pipe from the gas-holder is closed in the act of opening the carbide-holder to supply fresh carbid, and the generator is easily separable from the carbide-holder, so as to empty the spent carbid.

In the drawings, Figure 1 is a vertical section of the present improvement. Fig. 2 is an elevation at the side of the apparatus where the carbide-holder and the generator are located. Fig. 3 is a detached plan of the generator. Fig. 4 is a general plan view. Fig. 5 is an end view of the carbide-holder in a modified form, and Fig. 6 is a section of the carbide-supplying devices duplicated centrally of Fig. 5.

The carbide-holder is represented at A, and the cover B thereof is removable, and it is preferably hinged at 3 and provided with a clamping-screw or similar device at 4, and there is an incline at 5, forming the bottom of the carbide-holder, and this is sufficiently steep for the carbide to slide down the same, and there is an opening between the lower end of the inclined bottom and the side of the carbide-holder for the carbide to descend and pass into the rotary feeding device C, which is in the form of an open cone supported upon a shaft D, and the smaller end of the cone is closely adjacent to the place where the calcium carbide slides off the inclined bottom 5, so that such carbide passes into the rotary feeding device; but the angle of the conical rotary feeding device is such that the carbide will not slide through the same except when the feeding device is partially turned. Hence the feeding device becomes an obstruction to the movement of the calcium carbide except when it is moved, and when a turn or partial turn is given to this feeding device 50 the carbide slides through the open cone there-

cf and passes to the generator, as hereinafter described; but when the feeding device is stationary no carbide is passed into the generator.

Below the carbide-holder and the feeding device is a pipe 6, leading to the generator F, which is made as a tight case, and the joint G between the pipe 6 and the top of the generator vessel is made with flanges to receive between said flanges a washer of rubber or other material, and the clamping-screws at 7 allow for tightening the joint or for opening the same, so as to separate the generator from the carbide-holder and feeding device for the removal of such generator and the emptying of the spent material.

The generator F is adapted to holding water, and there is within it the removable basket E, which is perforated for allowing the water to reach the calcium carbide, so that as the carbide is dropped from the feeding device C into the generator it passes through the removable basket E and into the water, and the spent material can descend into the bottom of the generator and basket, and after the joint G has been separated and the generator F drawn aside the basket E can be drawn out from the generator and the spent material removed and fresh water introduced into the generator and the parts returned into position for use.

The gas-holder H is in the form of a cylinder closed at the top and open at the bottom, and this is within the water-holding vessel K, as usual, and the holder H rises and falls by the action of the gas within it, and there is a lever 1, pivoted at 8 and connected by the link 9 to the gas-holder, and there is at the other end a link 10 to the lever K', which has the shaft 16 for its pivot, and there is a ratchet-wheel 13 upon the shaft 16 and a pawl 12 upon the lever K', so that by the movement of this lever K' the shaft 16 can be turned and the feeding device revolved to a greater or less extent, and it is advantageous to have the gears 14 and 15 to connect the shaft 16 to the shaft D, so that the rotary feeding device will be turned with the required rapidity by the fall of the gas-holder for supplying calcium carbide into the generator, and when

the gas-holder is rising the pawl 12 will pass down over the teeth of the ratchet-wheel without turning the carbid-holder.

The gas as generated passes up through 5 the carbid-holder A to the pipe 18, and this descends and passes into the coil 19 at the bottom of the water in the vessel K, and the vertical pipe 20 opens into the gas-holder H, preferably above the water-line, and the gas 10 passes off by the pipe 21 and rising pipe 22 to the place where the gas is consumed, and it is sometimes advantageous to employ a cock 23 at the bottom of the pipe 22 to let out any fluid of condensation, and the cock 24 at the 15 lower end of the gas-pipe 18 is provided for a similar object.

The cock M is provided in the gas-pipe 18, and a handle L to the cock extends out over the cover B, so that as such cover B is swung 20 back the cock M is closed automatically in case the attendant fails to turn off the cock M before opening the carbid-holder. This prevents the gas from the holder H passing back and escaping through the cock M. A branch 25 pipe 25, connecting with the gas-pipe below the cock M, passes into the water-tank K, and there is above its lower end the escape-pipe 26. These are preferably at a pocket on the side of the said tank, and into this pocket 30 the water of the tank passes and forms a seal to the lower end of this pipe 25, so that if the pressure becomes excessive in the generator the gas may pass off through the safety-pipe 25 and into the pocket and escape by the pipe 35 26, and thus prevent undue pressure in the apparatus. I have represented the pivot 8 as supported upon the pipe 18.

In Fig. 6 the parts before mentioned are simply duplicated, with the two rotary feeding devices C C' upon the shaft D', which is made longer, the larger ends of the conical rotary feeding devices coming opposite each other, so that the carbid is discharged toward the center, and there may be segmental chutes 45 27 at the entrance to the rotary feeding devices, so as to direct the carbid into the smaller end of the conical feeding device.

I claim as my invention—

1. The combination with the generator and 50 the carbid-holder, of an incline within the

holder between the lower edge of which and the holder there is a discharge-opening, a horizontal shaft passing through the holder, an open-ended cone forming a feeding device mounted upon said shaft with the smaller end 55 toward the said discharge-opening, and means for feeding the carbid into the cone, substantially as specified.

2. The combination with the generator and the carbid-holder, of an incline within the 60 holder between the lower edge of which and the holder there is a discharge-opening, a horizontal shaft passing through the holder, an open-ended cone forming a feeding device mounted upon said shaft with the smaller end 65 toward the said discharge-opening, and a segmental chute 27 below the discharge-opening with the free end projecting into the cone for feeding the carbid into the cone, substantially 70 as specified.

3. The combination with the generator and the carbid-holder, of a double incline within the holder between the lower edges of which and the holder are narrow discharge-openings, a horizontal shaft passing through the 75 holder, two open-ended cones forming feeding devices mounted upon said shaft with the larger ends in opposition and the smaller ends toward the said discharge-openings, and means for feeding the carbid into the cones, 80 substantially as specified.

4. The combination with the generator and the carbid-holder, of a double incline within the holder between the lower edges of which and the holder are narrow discharge-openings, a horizontal shaft passing through the 85 holder, two open-ended cones forming feeding devices mounted upon said shaft with the larger ends in opposition and the smaller ends toward the said discharge-openings and segmental chutes 27 below the said discharge-openings with the free ends projecting into the cones for feeding the carbid into the cones, 90 substantially as specified.

Signed by me this 24th day of April, 1899. 95

ALONZO HICKS.
